UNITED STATES PATENT OFFICE.

WILLIAM L. DE REMER, OF CHICAGO, ILLINOIS.

RAIL-SECURING DEVICE.

1,083,436.

Specification of Letters Patent.

Patented Jan. 6, 1914.

Application filed September 21, 1911. Serial No. 650,579.

To all whom it may concern:

Be it known that I, WILLIAM L. DE REMER, a citizen of the United States, residing at Chicago, in the county of Cook and State of Illinois, have invented certain new and useful Improvements in Rail-Securing Devices, of which the following is a specification.

My invention relates to securing devices for railroad rails, and the object thereof is to provide a fastening or securing means which will not be affected by the creeping of the rails or the wave motion of the track except to tighten instead of loosening it, with the result that my fastening means always provides for firm and secure fastening of the rail and the tie plate (if used) to the tie.

Referring to the usual form of fastening means employing screw spikes, it has been found in practice, more particularly so on double track railways, that the screw spikes on the right-hand side of the running rails of the tracks remain tight, while the other screw spikes,—that is, those on the left-hand side of the running rails of the two tracks, loosen or back off, requiring continual attention and re-seating to maintain proper contact with the rails and with the tie plates, if they are used. I have discovered that this condition is due to the creeping of the rails and the wave motion of the track, and the effect thereof upon the screw spikes by reason of the contact of such rails therewith, either as to their heads or shanks, or both. It is well known in practice that, especially where the traffic is in one direction, the rails will move or creep in that direction (necessitating a class of rail anchors now commonly known as "anti-creepers"), and also that there is a wave motion of the track caused by the rolling load of the equipment, either motor, locomotive, cars, or the entire combination. Inasmuch as the screw spikes are in contact with the flanges of the rail, as above stated, it follows that when the ordinary screw spike, which has a right-hand thread, is used, the effect of this creeping movement is to tighten those which are located on the right-hand side of the running rails, inasmuch as the frictional contact between the rail and the spikes tends to turn the latter in a clockwise direction,—that is, in the direction for tightening them, so that perfect contact and proper rail-secur ing effect is maintained. On the other

hand, the same creeping movement of the rails causes the opposite effect upon those screw spikes which are located on the left-hand side of the running rails of each track; that is to say, this creeping movement, by reason of frictional contact with such spikes, turns the latter in an anti-clockwise direction,—that is, in a direction to loosen the same. This opposite rotation of these particular spikes is due to the fact that the frictional contact is on that side of the spike opposite to that of the spikes on the other side of the rails. As a result, the contact or abrasive points of the spikes cease to act against the rail, so that the latter loses its firm attachment to the tie until the spikes are reseated. However this constant loosening and reseating of the spikes are detrimental, as they cause enlargement of the spike holes and weakening of the tie, in case of the screw spike and a wearing of the thread in case the bolt and nut (or equivalent) are used. As a result the holding power and efficiency of the screw spikes or bolts are seriously impaired.

To overcome the above difficulty, I have provided a screw spike or bolt of the usual construction except that it has left-hand thread, and I employ such form of spike or bolts in the place of those which are ordinarily caused to loosen or back off from the rail. When these spikes or bolts are used in such situation, the creeping of the rails tends to tighten them in the same manner as the ordinary right-hand screw spikes or bolts on the right-hand side of the running rails. By the use of right and left hand screw spikes or bolts or the like, there are provided in actual practice two opposing forces against the rail, instead of one, with the result that a more secure and permanent fastening is afforded, and an effectual retarding medium against the rail movement provided. The points of frictional contact between spike and rail are materially increased by the use of a metal tie plate of proper construction, but, as will be understood, my invention in its broadest aspect does not require the use of such a plate.

While the conditions above described are more noticeable in double track railways, where practically all of the traffic in one direction is on one track, and all of the traffic in the other direction on the other track, yet, such conditions exist to some extent on a single track railway, for, as is well

known, it is generally the case that there is a greater traffic or heavier tonnage in one direction on a single track railway than in the other direction, so that there is more wave motion, and the rails are apt to creep more in one direction than in the other. Besides this, there are local conditions, such as grades and curves, which would cause a greater amount of creeping of rails in one direction than in the other, more or less regardless of the proportion of traffic in the two directions. It will therefore be understood that my new form of rail-securing means, including left-hand screw spikes, bolts or the like in places where the tendency is to loosen ordinary spikes, while useful to a greater extent and to a higher degree in double track railways, is also useful on single track railways.

My invention in its broader aspect is intended for and applicable to any character of rail securing device which is affected by creeping or wave movement of the rails and while in the present application I have shown several forms of such device, it will be understood that I do not limit myself specifically thereto but contemplate using my invention wherever applicable.

In the drawings, Figure 1 is a plan view of a section or portion of a double track railway, the same being what is known as a right-hand road; Fig. 2, a sectional elevation on the line 2—2 of Fig. 1; Fig. 3, a section on the line 3—3 of Fig. 1, but on a larger scale; Fig. 4, an elevation of my left-hand screw spike; Fig. 5, a plan view similar to Fig. 1, but on a larger scale and showing only the outer or right hand running rails and fastenings of a double track railroad of the right hand kind; Fig. 6, a section similar to Fig. 3, but on a larger scale, and illustrating the friction and contact points and also the friction point retainers and supports; and Figs. 7 and 8 detail views showing track fastening devices employing screw bolts as distinguished from screw spikes.

My invention in its present embodiment, and as herein illustrated, contemplates the employment of a tie plate of suitable construction, but, so far as my invention in its broader aspect is concerned, such tie plate may be wholly dispensed with. Nor is my invention limited to double track railways, inasmuch as the same may be used in connection with single track railways, as hereinbefore stated. However, I will proceed to describe my invention as used on a double track railway and in connection with a tie plate, but with the understanding that such invention is not limited thereto except as expressly specified in the claim. Moreover, my invention is applicable to rail securing devices employing either screw spikes or screw bolts, both of these attaching means being herein illustrated and described.

In Figs. 1 and 2, I have illustrated a portion or section of a double track railway of the right-hand type, having rail securing devices including tie plates and screw spikes, the direction of traffic being indicated by arrows. The right-hand running rails (which alone are shown in Fig. 5) of each track are indicated at 1, and the left-hand running rails at 2. In the present instance the rails rest upon tie plates 3 of suitable construction, and the latter are in turn supported upon cross-ties 4. While the tie plate may be of any usual or suitable construction, I prefer to employ the form herein shown, in which are provided bosses 3^a adjacent the spike holes and also a transverse shoulder 3^b at one end of the plate. The top surfaces of these bosses are so shaped or inclined as to correspond with the under side or face of the heads of the screw spikes hereinafter described, so that such heads will at their inner sides bear on the rail flanges and at their outer sides be supported by the bosses. Ordinarily the screw spikes employed have been of the right-hand type,—that is, with the threads suitably formed as right-hand threads, as indicated by the spikes 5 illustrated herein. As hereinbefore stated, spikes of this character remain properly applied or seated on the right-hand side of the running rails, but become loosened on the left-hand side of such rails, and I have discovered that this is due to the wave motion or creeping action of the rails in actual practice. To overcome this difficulty, therefore, I employ on the left-hand side of the running rails a different character of spike, the same being of the left-hand type,—that is, with the threads suitably formed as left-hand threads, such spikes being indicated herein at 6. The flanges of the rail are in contact, in the present instance, with both the heads of the spikes and with the shanks thereof, so that the same tendency acting to tighten the screw spikes 5 with the right-hand threads serves to tighten the screw spikes 6 with the left-hand threads, whereas, when all right-hand screw spikes are used, the tendency is to loosen those spikes located on the left-hand side of the running rails. The wave motion or creeping, especially on a double track railway, is in one direction only, so that by frictional contact between the rails and the screw spikes, those spikes on the right-hand side of the running rails will be turned or rotated in a clockwise direction so as to tighten or keep them seated, and, in the case of my new form of screw spikes located on the left-hand side of the running rails (speaking of a right-hand road), the same will be turned or rotated in an anti-clockwise direction, but, as the same have left-hand threads, they will thereby be tightened or kept seated.

The action of the rails upon the spikes at

the different friction and contact points will be apparent from an examination of Figs. 5 and 6. As clearly shown in these figures, there are friction and contact points, indicated at *a*, and also what I term friction point retainers and supporters, indicated at *b*. It will be noted that the points *a* are points of frictional contact between the rail flanges and the heads of the screw spikes, and also between the outer edges of said heads and the bosses of the tie plate, while the points *b* are the retainers and supports because they serve to retain and support the screw spikes in their proper applied position. The points of frictional contact at which the movements referred to take place between the rail and spikes are the points *a*, the tendency being always to rotate the spikes in the creeping or wave movement of the rails. These points are located at both the heads and shanks of the spikes inasmuch as in the particular instance under description both are in contact with the rail but it will be understood that the same action occurs where only the head or the shank has such contact.

For the purpose of making manifest the application of my invention to rail securing devices employing screw bolts I have shown in Figs. 7 and 8 two typical forms, one being used in connection with a wooden tie and the other with a metal tie, it being understood that other characters and constructions of tie, including the composite tie, and their rail fastenings may be used. Referring to Fig. 7, the fastening devices are two screw bolts 7 and 8, the former having left-hand threads and the latter right-hand threads, and both passing through the

tie 9 and secured by the two nuts 10 and 11 40 on the under side thereof. Referring to Fig. 8, the two screw bolts 12 and 13 have respectively left and right hand threads and pass through the metal tie 14, being secured thereto and to the tie plate 15 by the nuts 45 15 and 16.

When the tie plates are dispensed with, my new form of rail-securing structure is otherwise the same, and the action and result are the same.

By the use of my form of rail-securing means, the rail is maintained at all times and under all conditions in firm and permanent attachment to the tie; the rail, tie plate (if used), screw spike bolt or the like 55 and tie being united into a complete bond. Moreover I contemplate using my invention in any form or construction of rail-securing device to which it is applicable and therefore such invention is not to be limited to 60 any specific form unless expressly required by the claim. Furthermore, I use the designation "screw spikes" in the claim in its generic sense to include screw bolts and the like.

I claim:

In combination with a railroad rail, and a cross tie, rail securing means comprising a right-hand screw spike screwing into the tie on one side of the rail and a left-hand 70 screw spike screwing into the tie on the other side thereof, both said screw spikes being adapted to be tightened by the creeping action of the rail.

WILLIAM L. DE REMER.
